MANUFACTURE OF STAPLE FIBER YARNS
FROM CONTINUOUS FILAMENTSWilliam Ivan Taylor, Frank Corbyn Hale, and
Alfred Herbert Woodruff, Spondon, near Derby,
England, assignors to Celanese Corporation of
America, a corporation of DelawareOriginal application May 18, 1934, Serial No.
726,264. Divided and this application May 28,
1935, Serial No. 23,804. In Great Britain May
22, 1933

13 Claims. (Cl. 19—1)

This invention is a divisional of U. S. application S. No. 726,264 filed 18th May 1934, and relates to the manufacture of "spun" or staple fiber yarn from "continuous" filaments, i. e. filaments of considerable length as compared with the length of fiber required in the yarn to be produced or as compared with the short, naturally-occurring fibers such as, for example, cotton or wool, the object of the invention being to produce such yarn in which the physical characteristics of the original filaments are to a large extent retained, as well as to effect the production in a simple, expeditious, and cheap manner.

The formation of yarn containing staple fiber from "continuous" filaments is effected according to the invention by causing a bundle comprising a suitable number of filaments to pass in contact with the periphery of a cutting roller having sharp-edged flutes, the periphery of the roller moving in the same general direction as the filament bundle and at a different speed therefrom, and pressing the bundle against the periphery of the roller so that the flutes exert a cutting action on filaments in the bundle.

By reason of the relative motion between the filaments and the cutting surface, the filaments are readily cut with only a light pressure exerted on them at the cutting surface. There is, therefore, only a light gripping action on the bundle, with the result that the filaments in the bundle are subjected to relatively low tension.

It will, therefore, be seen that the method of the present invention is not one relying on the drafting of naturally-occurring fibers or fibers already formed by a cutting or like operation. On the other hand, the invention does not apply to the filaments a tension sufficient to break them. In fact, effecting the cutting of the filaments by pressing them against the flutes of the cutting roller is particularly advantageous in that it allows substantial retention of the physical properties (and especially extensibility) of the filaments in their conversion to fiber.

The points of cutting are distributed among the filaments, the cut filaments being transformed into fibers of an average length depending upon the frequency with which the filaments are cut. Such frequency, and consequently the average length of fiber, can be controlled by adjustment of various factors, e. g. by having a predetermined amount of twist in the bundle, as will appear later. Usually all the filaments in the bundle are transformed into staple fibers.

Movement of the surface of the fluted cutting roller in the same direction as the filaments as-

sists the feeding of the cut filaments in the bundle to and past the point where the bundle is engaged between the surface and the pressing means, and continuity of the material is maintained notwithstanding the conversion of filaments in the material into fibers. Conveniently, the pressing of the filaments into contact with the surface having the cutting action is effected by means of a roller the periphery of which also moves in the direction of motion of the filaments so as to facilitate continued forward feed of the filaments.

The pressing roller may move at the same speed as the cutting roller or at a different speed therefrom. For example both rollers may be positively driven at a speed which provides, in relation to the speed of passage of the filaments between them, the necessary slipping action so as to promote the cutting of the filaments. The pressing roller may, however, be conveniently driven by its engagement with the rotating cutting roller, in which case its speed is controlled by the speed of the driven roller, and in some cases to some extent by the speed of passage of the filaments.

Cutting of the filaments can also be effected by an inversion of the arrangement just described, i. e. by employing a fluted cutting roller driven by contact with a positively driven roller not necessarily having any cutting action. In this case the cutting roller presses itself against the filaments. Both rollers may have a fluted cutting surface, suitable constructions of such an arrangement being described hereafter.

Since continuity of the material as a whole must not be broken during the cutting of the filaments, the roller or rollers having the cutting action should not, under the pressure applied, sever more than one or relatively few of the filaments in the material at any point along the length of the material.

The bundle may be collected in any suitable manner. Thus, it may pass to a twisting and winding device which inserts twist while forming the bundle into any desired form of package. It is to be understood, however, that any twist originally in the bundle of filaments is not substantially removed by the operation of severing the filaments, and therefore remains in the bundle fed to the collecting device. Any additional twist imparted when collecting the bundle, as, for example, by winding the bundle by a cap or ring spinning device, is added to the remainder of such initial twist.

With the gripping device operating in a sub-

stantially non-slipping manner, the filament bundle may be converted into a fibrous bundle at a rate substantially equal to the peripheral speed of these rollers. At the same time, while 5 there is pressure exerted on the filaments at the cutting device, the filaments may be able to slip over the cutting surface at a rate which may be substantially the same as the rate of delivery of the product from the gripping device. 10 In other words, little, if any, elongation of the bundle takes place in the operation, since the conversion of the filaments into fibres, takes place by cutting and does not depend upon extension of the filaments to breaking point. However, 15 provided the physical properties of the filaments are substantially retained in the fibers produced, it is immaterial if a certain amount of reduction takes place in the size of the bundle during the passage of the filaments from 20 the cutting device to the gripping device.

The conversion may take place over a wide range of speeds, e. g. the fibrous product may be formed at a rate ranging from a few feet per minute up to 50, 75, 100, 150 or more yards per 25 minute. The invention therefore provides for the production of a yarn containing staple fiber direct from continuous filaments in a very simple, rapid, and cheap manner.

Subjecting of the material to more than one 30 cutting device brings about a reduction in average fiber length. Thus, material produced by one passage through an apparatus as above described may be passed again through the same or another apparatus, the amount of twist imparted to the material after the first passage being suitably regulated to enable it to withstand the further cutting treatment.

Again, additional twist may be added in a separate operation. For many purposes, however, 40 adequate twist can be inserted as the final step of the operation in which the filaments are converted into the yarn containing staple fiber. Thus, about 3 turns per inch may be added by a cap-spinning device to give a yarn particularly suited to use in knitting machines. In fact, although such twist is quite low for a 45 staple fiber material, the strength of the yarn is quite considerable, probably due to longer fibers being mixed with shorter ones.

50 The carrying out of the invention will now be described by way of example with reference to the accompanying diagrammatic drawing, in which

Fig. 1 shows a cutting-roller device and a gripping-roller device disposed substantially horizontally with respect to each other;

Fig. 2 shows a cutting-roller device and a gripping-roller device disposed substantially vertically one above the other;

Fig. 3 shows a modified form of apparatus also utilizing a vertical disposition of the roller pairs;

Fig. 4 is a detailed view of the cutting roller pair;

Fig. 5 shows a modified cutting device; and

Fig. 6 is a front elevational view of the rollers showing the fluted cutting surfaces.

Referring to Fig. 1, a bundle of filaments 10 of denier in accordance with the denier of the 70 products desired is fed between a pair of rollers 11, 12 and then between a further pair of rollers 13, 14. The roller 14 is provided with smooth flutes and the roller 13 is covered with rubber or the like and suitably loaded so that the two 75 rollers firmly grip the bundle. The roller 12 is

provided with a cutting surface of sharp-edged flutes. The roller 11 lightly presses the bundle 10 against the periphery of the roller 12.

The roller 14 is driven at a speed in excess of that of the roller 12 so that by reason of the firm grip exerted between the rollers 13, 14 the bundle 10 is caused to slip over the periphery of the cutting roller 12. There is light pressure between the rollers 11 and 12 and the slip permitted by these rollers, and the bundle drawn between the rollers has its filaments severed at frequent intervals so that after leaving the rollers 11, 12 the bundle contains staple fibers, the protruding ends of which are diagrammatically indicated in the figure.

15 The rollers 11, 13 may rotate solely by their contact with the driven rollers 12, 14, it being understood, however, that an inversion of the roller arrangements is possible; for example the cutting roller 12 may rest upon and be driven by its contact with the non-cutting roller 11. Again, both rollers 11, 12 may provide a cutting action.

20 Referring now to Fig. 2, the filament bundle 10 is shown supplied from a bobbin 15 and led to a pair of rollers 11, 12 as described with reference to Fig. 1. Gripping rollers 13, 14 are disposed below the roller 12 so that the bundle 10 passes over an arc of the roller 12 and vertically downwards to the nip of the rollers 13, 14. The roller 13 is carried on an arm 18 pivoted at 19 and is pressed against the roller 14 by a cord 20 attached to the arm and carrying a weight 21 sufficient to provide the gripping and 25 preferably non-slipping action of the rollers 13, 14.

30 The arrangement of Fig. 2 thus provides the application of any desired amount of pressure at the pair of gripping rollers, while allowing for an independent amount of pressure being exerted 35 between the rollers 11, 12. Thus, the roller 11 can be self-loaded as shown in Fig. 4, the roller having a spindle 22 working in a slotted bearing 23 so that the roller 11 rests by its own weight 40 on the roller 12.

45 The roller 11 may be rigid and so formed as to have the desired weight for the loading required, or it may consist of a resilient core 24, e. g. of sponge rubber or other soft rubber, within a flexible sheath 25, e. g. of thin metal tubing which 50 provides a hard though flexible surface by which the filaments are pressed against the cutting periphery of the roller 12.

55 The cutting roller is made of steel or other hard material having flutes running generally transverse to the direction of motion of the filaments, e. g. helical flutes as shown at 34 in Fig. 6. These flutes have sharp edges over which the filaments are drawn as they slip between the cutting roller and the pressing surface. For example, the roller may have semi-circular, triangular, or rectangular flutes forming with the surface of the roller a clean edge against which the filaments are pressed. The cutting roller 35 shown in Fig. 6 is driven by its shaft 36 with 60 the desired speed and in the required direction, and the pressing roller 37 is driven by its contact with the roller 35. The roller 37 is shown fluted to form a cutting surface, the helical flutes of one roller crossing those of the other at an 65 angle at their points of contact.

70 In Fig. 3, the bundle 10 is supplied from a rotating bobbin 16 so as to add twist to the bundle before it is subjected to the action of the cutting device. Both rollers 11, 13 are arranged 75

to be pressed against their corresponding rollers 12, 14 by the cord and weight arrangement 20, 21. For this purpose the rollers 11, 13 are mounted on a bar 26 pivotally mounted at 27 on the arm 18, the point 28 (preferably adjustable) at which the cord 20 is attached to the bar 26 being such that the requisite pressures may be exerted by the rollers 11, 13 to provide for the cutting action of the one roller pair and the gripping action of the other respectively.

In Fig. 2 the yarn containing the staple fiber is shown being collected by a cap spinning device 29 operating to insert any desired amount of twist. In Fig. 3 collection is effected by a ring-spinning device 30. If desired, the yarn may be lubricated before being twisted, for example by carrying it over a wick 128, roller or other device supplied with lubricant and arranged between the rollers 13, 14 and the balloon guide 31 of the twisting device. Again, lubricant may be sprayed on to the yarn.

The distance between the rollers 11, 12 and the gripping rollers 13, 14 is such that the rollers 13, 14 take control of the fibrous bundle soon after cutting so as to feed it continuously to the collecting device.

In Fig. 5, the bundle 10 is carried into slipping contact with the cutting roller 12 by means of gripping rollers 13, 14 and the filaments are pressed against the roller 12 by the surface of a stationary member 32 suitably weighted and carried in a slotted bearing 33 so as to rest on the roller 12. By reason of the pressure applied and the slippage of the bundle between the roller 12 and the member 32, the roller 12 cuts filaments in the bundle at frequent intervals.

The average length of staple fiber has an important bearing on the appearance and other qualities of the product produced according to the invention. This may be controlled by suitable adjustment of the apparatus and its conditions of operation, as well as by selection of the filaments to be treated. Thus, in general, a higher rate of operation of the apparatus results in a longer average fiber length being obtained. A greater amount of twist in the filament bundle tends to reduce the average fiber length. Again, greater pressure at the cutting device (this pressure depending also upon the size of the filament bundle to be treated) reduces the average fiber length, as also does an increase in the ratio between the speeds of the feeding and cutting devices. Finer filaments are usually more readily cut, and the more frequent breakage has the effect of reducing the average fiber length.

As indicated above, greater pressure at the cutting device is necessary with increase in the size of the filament bundle. Finer filaments, however, require less pressure than coarser filaments. Again, a lower ratio between the speeds of the feeding and cutting devices calls for higher pressure.

As regards the effect of the distance between the cutting and gripping devices on the length of staple, it may be noted that at the most only a small percentage of the fibers in the staple fiber yarn are less in length than this distance.

What we claim and desire to secure by Letters Patent is:—

1. Process for the conversion of continuous filaments directly into a continuous product containing staple fiber, which comprises causing a bundle of continuous filaments to pass in contact with the surface of a fluted cutting roller moving

substantially the same direction as said filaments but at a peripheral speed different from the speed of the filaments, and pressing the bundle against the surface of the roller so that during the rotation of the roller the bundle is continuously nipped substantially at a point in its length and is subjected at said point to a cutting action that at any one point severs part only of the filaments in the bundle, the movement of the filaments past the surface of the roller causing the partial severing action to take place progressively along the length of the filaments.

2. Process for the conversion of continuous filaments directly into a yarn containing staple fiber, which comprises causing a twisted bundle of continuous filaments to pass in contact with the surface of a fluted cutting roller moving in substantially the same direction as said filaments but at a peripheral speed different from the speed of the filaments, and pressing the bundle against the surface of the roller so that during the rotation of the roller the bundle is continuously nipped substantially at a point in its length and is subjected at said point to a cutting action that at any one point severs part only of the filaments in the bundle, the movement of the filaments past the surface of the roller causing the partial severing action to take place progressively along the length of the filaments.

3. Process for the conversion of continuous filaments directly into a yarn containing staple fiber, which comprises causing a bundle of continuous filaments to pass in contact with the surface of a fluted cutting roller moving in substantially the same direction as said filaments but at a peripheral speed different from the speed of the filaments, pressing the bundle against the surface of the roller so that during the rotation of the roller the bundle is continuously nipped substantially at a point in its length and is subjected at said point to a cutting action that at any one point severs part only of the filaments in the bundle, the movement of the filaments past the surface of the roller causing the partial severing action to take place progressively along the length of the filaments and collecting the treated bundle as a yarn by a twisting and winding operation.

4. Process for the conversion of continuous filaments directly into a continuous product containing staple fiber, which comprises causing a bundle of continuous filaments to pass in contact with the surface of a fluted cutting roller moving in substantially the same direction as said filaments but at a peripheral speed different from the speed of the filaments, and pressing the bundle against the surface of the roller by the surface of a second fluted cutting roller so that the bundle is continuously nipped substantially at a point in its length and is subjected on two sides at said point to a cutting action that at any one point severs only part of the filaments in the bundle, the movement of the filaments past the surface of the roller causing the partial severing action to take place progressively along the length of the filaments.

5. Process for the conversion of continuous filaments directly into a continuous product containing staple fiber, which comprises causing a bundle of continuous filaments to pass between a stationary surface and the surface of a fluted cutting roller moving in substantially the same direction as said filaments but at a peripheral speed different from the speed of the filaments, and applying pressure to the bundle by the stationary surface

in such a manner that during the rotation of the roller the bundle is continuously nipped substantially at a point in its length and is subjected at said point to a cutting action that at any one point 5 severs part only of the filaments in the bundle, the movement of the filaments past the surface of the roller causing the partial severing action to take place progressively along the length of the filaments.

10. 6. Process for the conversion of continuous filaments directly into a continuous product containing staple fiber, which comprises drawing a bundle of continuous filaments over the surface of a fluted cutting roller moving at a less speed than 15 the filaments but in substantially the same direction, and pressing the bundle against the surface of the roller so that during the rotation of the roller the bundle is continuously nipped substantially at a point in its length and is subjected 20 at said point to a cutting action that at any one point severs part only of the filaments in the bundle, the movement of the filaments past the surface of the roller causing the partial severing action to take place progressively along 25 the length of the filaments.

7. Apparatus for the conversion of continuous filaments directly into a continuous product containing staple fiber, comprising a rotatable fluted cutting roller, means for causing a bundle of 30 continuous filaments to move over said roller, means with which the fluted surface of the roller forms a nip at a point in the length of the surface of the roller, considered in the direction of movement of the surface of the roller, to keep the filaments continuously pressed against the fluted surface substantially at a point in the length of the filaments, and means for causing the roller to rotate so that its surface moves in substantially 35 the same direction as the bundle but at a speed different from that of the bundle.

8. Apparatus for the conversion of continuous filaments directly into a continuous product containing staple fiber, comprising a rotatable helically fluted cutting roller, means for causing a 40 bundle of continuous filaments to move over said roller, means with which the fluted surface of the roller forms a nip at a point in the length of the surface of the roller, considered in the direction of movement of the surface of the roller, to keep the filaments continuously 45 pressed against the fluted surface substantially at a point in the length of the filaments, and means for causing the roller to rotate so that its surface moves in substantially the same direction as the bundle but at a speed different from that of the bundle.

9. Apparatus for the conversion of continuous filaments directly into a continuous product containing staple fiber, comprising a rotatable fluted cutting roller, means for causing a bundle of continuous filaments to move over said roller, a 5 rotatable roller with which the fluted surface of the roller forms a nip to keep the filaments continuously pressed against the fluted surface substantially at a point in the length of the filaments, and means for causing the roller to rotate so that its surface moves in substantially the same direction as the bundle but at a speed different from that of the bundle. 10

10. Apparatus according to claim 9 wherein the pressing roller has a surface comprising a flexible 15 metal tube.

11. Apparatus according to claim 9 wherein the pressing roller comprises a flexible metal tube and a resilient core on which the tube is mounted.

12. Apparatus for the conversion of continuous filaments directly into a continuous product containing staple fiber, comprising a pair of contacting rollers, at least one of which is a fluted cutting roller, lightly pressed together to form a nip, a further pair of rollers firmly pressed together, and means to drive at least one of each pair of rollers, so that the second pair of rollers move with a peripheral speed greater than the first pair of rollers, the second pair of rollers being 20 adapted to grip a bundle of continuous filaments and pull the bundle through the nip of the cutting pair of rollers at a speed different from the speed 25 of the surfaces of said rollers. 30

13. Apparatus for the conversion of continuous filaments directly into yarn containing staple fiber, comprising a rotatable fluted cutting roller, means for causing a bundle of continuous filaments to move over said roller, means with which the fluted surface of the roller forms a nip at a point in the length of the surface of the roller, considered in the direction of movement of the surface of the roller, to keep the filaments continuously pressed against the fluted surface substantially at a point in the length of the filaments, means for causing the roller to rotate so that its surface moves in substantially the same direction as the bundle but at a speed different from that of the bundle, a twisting and winding 40 device to collect the treated bundle and a lubricator disposed between the second pair of rollers and the twisting and winding device so as to contact with the bundle. 45
